UNITED STATES PATENT OFFICE.

ABRAHAM NOVICK, OF NEW YORK, N. Y., ASSIGNEE TO F. L. SCHMIDT COMPANY, OF
NEW YORK, N. Y., A CORPORATION OF NEW YORK.

BLANK-FEEDING MECHANISM.

1,296,690.

Specification of Letters Patent. Patented Mar. 11, 1919.

Application filed November 21, 1917. Serial No. 203,136.

To all whom it may concern:

Be it known that I, ABRAHAM NOVICK, a citizen of the United States, and a resident of New York, borough of Manhattan, in the county of New York and State of New York, have invented certain new and useful Improvements in Blank-Feeding Mechanisms, of which the following is a specification.

10 This invention relates to blank feeding mechanisms and has for its object to provide means of the class specified characterized by simplicity and accuracy of operation at high speed.

15 To these ends my improvements comprise features illustrated in their preferred embodiment in the drawings accompanying this specification wherein:—

Figure 1 is a diagrammatic side elevation 20 of so much of a blank feeding mechanism as will suffice to clearly illustrate my improvements. Fig. 2 is a view similar to that of Fig. 1 and showing the parts in different relative positions. Fig. 3 is a similar side 25 elevation to those of Figs. 1 and 2, illustrating the cams and gears of the mechanism. Fig. 4 is a plan view of one form of blank which the machine is adapted to feed. All 30 of the figures of the drawings are to one scale.

A pile of blanks 2 may be arranged with the leading ends of said blanks conveniently disposed relatively to the parts of the mechanism designed to operate upon those blanks. Said pile may be guided by rods 3 and 4 in engagement with reentrant corners on said blanks, Fig. 4, and may be supported by table 38. Also, preferably, said blanks are elevated at their rearward ends, so that gravity assists in keeping them in engagement 40 with said rods 3 and 4. Said table 38 may be elevated from time to time, through the instrumentality of link 14, by some convenient known means, not shown, to maintain the top of the pile at a convenient position 45 relatively to the lower position of picker 6. Said picker may be of some accepted character, which for convenience is here illustrated as a pneumatic picker. Also said picker is carried by oscillating frame 7 turning 50 on the fixed axis of shaft 8 and air may be exhausted therefrom at suitable times through pipe 9 by some known means, not shown.

55 Mounted on rotatable shaft 10 having a

fixed axis a short distance above the leading ends of the blanks in pile 2, is large, upper, segmental feed roll 11, the operative portion of its periphery 12 extending about half the circumference thereof and the remaining 60 portion 13 being of less radius. Oscillatable shaft 8, to which frame 7 is fixed, also has fixed thereto bell-crank 18, arm 19 of which is pivotally connected at 20 to bar 21, carrying roll 22 for engagement with cam 23, 65 turning about the fixed axis of shaft 24. Said arm 19 is slotted at 39, so that pivot 20 of bar 21 may be shifted toward and from shaft 8 and the stroke of bell-crank 18 and picker 6 thereby adjusted. Said roll may be 70 urged to engagement with said cam by spring 36. By this means said picker 6 may be oscillated from the position of Fig. 1, in engagement with upper blank 5 of pile 2, 75 to the position of Fig. 2, for lifting the leading end of the said blank into engageable position adjacent to or against the under side of feed roll 11. To the other arm of bell-crank 18 link 14 is pivotally connected.

On shaft 15, having a fixed axis below feed, 80 roll 11 and also below the level of the top of the pile of blanks, is oscillatably mounted arm 16, carrying on its free upper end small lower feed roll 17. Said arm 16 may be oscillated by means of roll 25 in engagement 85 with cam 26 fixed to shaft 24, to which cam 23 also is fixed. Said roll 25 is carried by arm 27 fixed to shaft 15, to which arm 16 also is fixed. Said roll 25 may be urged to engagement with said cam 26 by spring 37, 90 one end of which is fixed to arm 16 and the other end to a fixed part of the machine. Small lower feed roll 17 is mounted for bodily movement from its idle position of Fig. 1 at the left of the pile of blanks, to its operative position over the leading end of the pile of blanks and under the leading end of lifted upper blank 5 of that pile, Fig. 2, 95 for coaction with roll 11.

Upper roll 11 may be in the form of two 100 disks, only one of which is shown, and picker 6 may swing up between said disks; or roll 11 may have a relatively narrow face and picker 6 may swing upwardly close beside it as shown.

105 Referring now particularly to Fig. 3, the gearing for my improved mechanism is illustrated diagrammatically by dot and dash pitch lines, wherein gear 28 is fixed to shaft 24 and which shaft may be considered the 110

driving shaft. Said gear is twice the size of and meshes with and drives gear 29 fixed to shaft 10, whereby roll 11, also fixed to said shaft, is caused to make two revolutions for each revolution of shaft 24 and the cams thereon. Thus roll 11 makes one idle revolution between each two operative revolutions in coaction with roll 17. Also fixed to shaft 10 is gear 30, two and one half times the size of gear 31, with which it meshes and which it drives. Said gear 31 turns freely on oscillatable shaft 15.

Coaxial with and fixed to gear 31 is small gear 32. Said gear 32 meshes with intermediate gear 33, mounted on arm 16, which in turn meshes with gear 34, fixed to shaft 35, to which feed roll 17 is fixed. Gears 32, 33 and 34 are of equal size. Roll 11, in its operative segment, is two and one half times the diameter of roll 17, so that, by means of the gearing just described said rolls will be driven in opposite directions at the same surface speed, roll 11 in clockwise direction and roll 17 in anti-clockwise direction.

25 The operation of my improved blank feeding mechanism is as follows: A pile of blanks being so positioned, against rods 3 and 4; that upper blank 5 thereof is in engaging relation with picker 6 when that picker is in its lower position, Fig. 1, and the leading end of high portion 12 of upper feed roll 11 being about three-eighths of a revolution from engaging position with lower feed roll 17, and said lower feed roll being in its 30 retracted position, cam roll 22, of bar 21, is engaged by the rising portion of cam 23, whereby bell-crank 18 is oscillated in clockwise direction and picker 6, from which the air is at this time exhausted, is swung upwardly, carrying top blank 5 therewith, thus delivering the leading end of that blank against the under side of said roll 11, just as the leading end of the high portion 12 thereof rotates to a position contiguous to said leading end of said blank. Shortly after picker 6 has started on its upward movement, cam roll 25 is engaged by the rising portion of cam 26 and lower feed roll 17 is swung toward the right, Fig. 2, and 35 passes under the lifted top blank 5, over the remaining blanks on the pile and into coaction with upper feed roll 11 just as the leading end of the high portion 12 of that roll engages blank 5. The leading end of said blank is thereby gripped between said feed rolls and air is supplied to picker 6, whereby that picker releases its hold on the blank. Said feed rolls 11 and 17, continuing their coaction, the blank is advanced in accurate predetermined timing. Also each successive blank is gripped and advanced in accurate timing with said first blank.

60 Said rolls 11 and 17 may thus deliver said blank in accurate timing to mechanism not shown, adapted to perform desired opera-

tions on said blank. Said delivery to other mechanism should be accomplished before, or not later than, the arrival of the following end of high portion 12 of roll 11 opposite roll 17, as at that time said rolls complete their period of coaction in control of said blank.

70 Coincidently with or directly after said rolls complete their period of coaction, cam roll 25 will be engaged by the succeeding 75 lower portion of cam 26 and lower feed roll 17 will be swung to the left, off and away from the pile of blanks, from the position of Fig. 2 to that of Fig. 1. At about the same time cam roll 22 will be engaged by 80 the falling portion of cam 23, and bar 21 will swing picker 6 downwardly, just as lower feed roll 17 recedes to permit it to, pass therebehind. Said picker will then 85 pass again into engagement with the uppermost blank on the pile and the recited operation will be repeated.

I claim:

1. A blank feeding mechanism including in combination, means for supporting and 90 guiding a pile of blanks, a pair of feed rolls one of which is mounted on a fixed axis and is intermittently operable and the other of which is mounted on a movable axis, means for moving said movable axis roll into coacting relation with said fixed axis roll, during the operable period of said fixed axis roll, means for lifting the leading end of the upper blank into engageable relation with said fixed axis roll while said movable axis roll is 95 out of coacting relation with said fixed axis roll, and means for rotating said feed rolls in opposite directions, respectively, at the same peripheral speed.

100 2. A blank feeding mechanism including in combination, means for supporting and guiding a pile of blanks, an intermittently operable upper feed roll, means for lifting the leading end of the upper blank into engageable relation with said upper feed roll, 105 a lower feed roll mounted for movement into and out of the path of the leading end of said blank from the pile to its lifted position, said upper feed roll being adapted for coaction with said lower feed roll when that 110 lower roll is moved into said path of the leading end of the blank, means for moving said lower feed roll into coacting relation with said upper feed roll after said blank has been lifted, and means for rotating said 115 feed rolls in opposite directions, respectively, at the same peripheral speed.

120 3. A blank feeding mechanism including in combination, means for supporting and 125 guiding a pile of blanks, an intermittently operable upper feed roll, an oscillating picker for lifting the leading end of the upper blank into engageable relation with said upper feed roll, a lower feed roll mounted for movement into and out of the 130

- path of the leading end of said blank from the pile to its lifted position, means for moving said lower feed roll into coacting relation with said upper feed roll after said blank has been lifted, said upper feed roll being adapted for coaction with said lower feed roll when that lower roll is moved into said path of the leading end of the blank, and means for rotating said feed rolls in opposite directions, respectively, at the same peripheral speed.
4. A blank feeding mechanism including in combination, means for supporting and guiding a pile of blanks, an upper feed roll means for lifting the leading end of the upper blank into engageable relation with said upper feed roll, a lower feed roll mounted for movement into and out of the path of the leading end of said blank from the pile to its lifted position, means for moving said lower feed roll into coacting relation with said upper feed roll after said blank has been lifted, said upper feed roll having a segmental periphery adapted for coaction with said lower feed roll when that lower roll is moved into said path of the leading end of the blank, means for rotating said feed rolls in opposite directions, respectively, at the same peripheral speed, and means for timing the movement of said lower roll with the leading end of the segmental periphery of said upper roll.
5. A blank feeding mechanism including in combination, means for supporting and guiding a pile of blanks, an intermittently operable upper feed roll, a picker for lifting the leading end of the upper blank into engageable relation with said upper feed roll, means for adjusting the stroke of said picker, a lower feed roll mounted for movement into and out of the path of the leading end of said blank from the pile to its lifted position, said upper feed roll being adapted for coaction with said lower feed roll when that lower roll is moved into said path of the leading end of the blank, means for moving said lower feed roll into coacting relation with said upper feed roll after said blank has been lifted, and means for rotating said feed rolls in opposite directions, respectively, at the same peripheral speed.
6. A blank feeding mechanism including in combination, means for supporting and guiding a pile of blanks, a pair of feed rolls, one of which is mounted on a fixed axis and is intermittently operable and the other of which is mounted on a movable axis, means for moving the leading end of the upper blank into engageable relation with said fixed axis roll while said movable axis roll is out of coacting relation with said fixed axis roll, one of said rolls having a segmental periphery adapted for coaction with the other roll, means for moving said movable axis roll into and out of coacting relation with the other roll, and means for rotating said feed rolls in opposite directions, respectively, at the same peripheral speed.
7. A blank feeding mechanism including in combination, means for supporting and guiding a pile of blanks, an intermittently operable upper feed roll, means for lifting the leading end of the upper blank into engageable relation with said upper feed roll, a lower feed roll carried on the free end of an oscillatable arm for swinging said roll into and out of the path of the leading end of said blank from the pile to its lifted position, said upper feed roll being adapted for coaction with said lower roll when that lower roll is swung into said path of the leading end of the blank, means for oscillating said arm for swinging said lower roll into coaction with said upper roll, and means for rotating said feed rolls at the same peripheral speed, but in opposite directions, respectively, during their coaction.
8. A blank feeding mechanism including in combination, means for supporting and guiding a pile of blanks, an upper intermittently acting feed roll, means for lifting the leading end of the upper blank into engageable relation with said upper roll, a lower feed roll mounted for movement into and out of the path of the leading end of said blank from the pile to its lifted position, means for moving said lower roll into coacting relation with said upper roll after said blank has been lifted, means for rotating said feed rolls at the same peripheral speed but in opposite directions, respectively, during their coaction, and means for timing the movement of said lower roll with the intermittent action of said upper roll.
9. A blank feeding mechanism including in combination, means for supporting and guiding a pile of blanks, a pair of feed rolls, one of which is intermittently operable and the other of which is movable into coacting relation with said intermittently operable roll during its period of operability, means for lifting the leading end of the upper blank into engageable relation with said intermittently operable roll when the other roll is out of coacting relation therewith, and means for rotating said feed rolls in opposite directions, respectively, at the same peripheral speed during their period of coaction.

Signed at New York, in the county of New York and State of New York, this 20th day of November, 1917.

ABRAHAM NOVICK.
